(57) **CLAIM**

The ornamental design for a furniture leg slider, as shown and described.

DESCRIPTION

FIG. 1 is a top, front, perspective view of the furniture leg slider;

FIG. 2 is a bottom, front, perspective view thereof;

FIG. 3 is a right side elevation view thereof;

FIG. 4 is a left side elevation view thereof;

FIG. 5 is a front elevation view thereof;

FIG. 6 is a back elevation view thereof;

FIG. 7 is a top plan view thereof; and,

FIG. 8 is a bottom plan view thereof.

The broken lines shown in FIG. 1 and FIG. 7 are for the purpose of illustrating portions of the furniture leg slider that form no part of the claimed design.

1 Claim, 7 Drawing Sheets
